UNITED STATES PATENT OFFICE.

WALTER R. BARKER AND LOUIS JENSEN, OF CHICAGO, ILLINOIS, ASSIGNORS TO UNITED AUTOGRAPHIC REGISTER CO., OF CHICAGO, ILLINOIS, A CORPORATION OF ILLINOIS.

AUTOGRAPHIC REGISTER.

Application filed February 9, 1922. Serial No. 535,293.

Our invention relates to autographic registers, and particularly to that class of registers in which the strips of the paper records are provided with alining postholes at the 5 end of each ticket printed on the strips, that come into registry with the friction rollers in order to stop the progress of the records.

One of these rollers is provided with a laterally movable collar that is brought into 10 play when it is desired to expel the record. The object of the invention is to improve the means employed to manipulate this collar every time it is desired to start the expulsion of the paper strips. This we accomplish by the certain construction and arrangement of parts to be hereinafter more 15 specifically pointed out, and as claimed.

In the drawings:
Figure 1 is an end view of that end of an 20 autographic register to which our improvements are applied with portions broken away.

Figure 2 is a similar view thereof showing parts thereon in different positions.
Figure 3 is an end view of portions thereof.
Fig. 4 is a schematic view of the feed 25 roller and co-acting disk operating upon two strips of perforated paper.

Referring to the drawings, A, A, represent the side walls of the discharge end of 30 an autographic register, and B represents a reversely channeled transverse hood, the closed flanged end edges of which are secured in any suitable manner to the top edges of the side walls A, A. A solid transverse roller C is placed longitudinally in this hood, and the ends thereof are journaled in the closed ends of the same.

The upper edges of the side walls, A, A, 40 are provided with bearings, 2, 2, for the tubular shaft 3, on which the friction devices for cooperating with the postholes in the paper record are mounted. These devices comprise sleeves, 5 and 6, respectively, that 45 are placed one on each side of the center of length of the shaft 3, and are each provided with corresponding circumferential separated flanges 7, 7, that are located so as to come in alinement with the postholes in 50 the record strips that are passed through the register.

The portion nearest the center of the shaft, has a collar 8 secured thereto, substantially

as shown in the drawings. Immediately next the collar, on the right side thereof, we 55 surround the shaft with an exteriorly milled or otherwise roughened annulus 9, and the interior bore of which is bevelled, and, of a greater diameter than the tubular shaft. On the adjacent end of said tubular shaft, 60 we mount a cone 10, the exterior of which corresponds to and is at the same angle as the interior bore of annulus 9. This cone has a reciprocal motion to and from collar 9, toward which it is kept bearing by means 65 of a coil-spring 12, wound around the shaft, between the ends of the cone and the adjacent flange 7 of sleeve 5. This cone is designed to revolve with shaft 3, whose outer end is extended and has a crank 14 securely 70 mounted thereon. The cone is secured by means of a transaxial pin 15, that extends through a longitudinal elongated slot 16 in the adjacent portion of the shaft 3, and transaxially through an inner longitudinally 75 extending solid shaft 17. This shaft 17 extends through the bore of the tubular shaft 3 and has its outer end, 18, screw-threaded, and, when the cone engages the collar, and raises it so that it is concentric to the shaft, 80 the screw-threaded end of said shaft 17 will project beyond the bearing in the sidewall 85 opposite the handle, substantially as shown in Figure 2.

At a suitable point below the tubular shaft, 90 there is a transverse rock-shaft 19 that has bearings in the sidewalls of the supporting-frame, beyond which its ends extend. At one end rock-shaft 19 has a downwardly projecting arm 20, by means of which it is 95 manipulated, and at its opposite projecting end it has a curved arm 21 secured thereto and projecting upward therefrom. The upper end of this arm 21 has a recess or notch 22 in its rear vertical edge, and the 100 dip of this notch is so shaped that when shaft 17 is in the position shown in Figure 2 of the drawings, it will engage the screw-threaded end 18 of the same, and hold it against its return to the position shown in Figure 1 of the drawings. This arm 21 is kept pressing toward the rear of the register by means of a coil contraction spring 23, one end of which is attached to the upper 105 end of said arm and the rear end to a suitable stud secured in the sidewall A.

In operation arm 20 is pushed down thus withdrawing an arm 21 from in front of the end of shaft 17. Shaft 17 moves out past arm 21 (spring 16 forces it out). Cone 10 is fastened to shaft 17 by means of the transverse pin 15, and as spring 16 pushes against the end of cone 10, it causes the cone to engage annulus 9 and move said annulus transversely into position, concentric to the 10 axis of the tubular shaft and into contact with the upper feed roller C. Handle 14 is then turned and causes the annulus to engage and bear against the periphery of the solid roller C, and starts the expulsion of 15 the record strips.

The end of shaft 17 engaged by arm 21 has a thread cut in it. Arm 21 also has a thread in recess 22 that engages with the thread on shaft 17 and spring 23 tends to 20 draw one into the other.

As handle 14 is rotated it rotates shaft 17 (pin 15 in the cone passes through the tubular shaft 4), and as shaft 17 rotates it moves back into the tubular shaft, due to the engagement of the threaded portions of arm 25 21 and shaft 17 thereby withdrawing cone 10 from annulus 9 and disengaging the latter from the paper strips.

When the threaded portion of shaft 17 30 has been moved back clear of arm 21, arm 21 shoots past the end of shaft 17 and thus keeps the shaft from again coming out of the tube and keeps the cone from engaging with the collar until arm 20 is again pushed 35 down.

When the arm 21 moves down its side bears against the end of the solid shaft 17 and holds the cone in disengagement from the collar 9 while the flanges 7, 7, which in 40 the meantime have engaged the paper strips, will feed them out of the register until the postholes in said strips come into registry with the segments of the flanges that contact the roller C, whereupon the outward movement of the strips will stop. This action is both collective and individual with the strips and feeds the same until the apertures in the respective strips are in registry.

50 What we claim as new is:

1. An autographic register comprising a transverse upper discharge roller, a tubular shaft, an annulus mounted on and having a central opening larger than said shaft, and a reciprocable cone concentric and revolvable with said shaft, and means for reciprocating said cone.

2. An autographic register comprising an upper transverse discharge roller, a tubular 60 shaft, an annulus mounted on and having a central opening larger than said shaft, a solid shaft within said hollow shaft, a reciprocable cone concentric and revolvable with the same and secured thereto by means of a transverse pin extending through a solid shaft when the cone is out of engage-

longitudinal slot in the tubular shaft, and means for reciprocating said solid shaft.

3. An autographic register comprising an upper transverse discharge roller, a tubular shaft, an annulus mounted on and having a central opening larger than said shaft, a solid shaft within said hollow shaft, a reciprocable cone concentric and revolvable with said shafts and secured thereto by means of a transverse pin extended through 75 a longitudinal slot in the tubular shaft, means for reciprocating said solid shaft, and a coiled expansion spring pressing said cone toward said annulus.

4. An autographic register comprising an upper transverse discharge roller, a shaft, separated circumferential flanges mounted on said shaft in alinement with the post-holes formed in the paper strips, an annulus of substantially the same diameter as said 80 flanges having a central opening of greater diameter than the portion of the shaft upon which it is mounted, a reciprocable cone that engages the central opening of the annulus, and means for actuating said cone. 85

5. An autographic register comprising an upper transverse discharge roller, a tubular shaft, separated circumferential flanges mounted on said tubular shaft in alinement with the postholes formed in the paper 90 strips, an annulus of substantially the same diameter as said flanges having a central opening of greater diameter than the portion of the tubular shaft upon which it is mounted, a reciprocable cone that engages 95 the central opening of the annulus, a solid shaft seated in the bore of said tubular shaft, a transverse pin that extends from said cone to the solid shaft through a longitudinally elongated slot in the tubular shaft and means 100 for actuating said solid shaft.

6. An autographic register comprising an upper transverse discharge roller, a tubular shaft, a shaft within said tubular shaft, an annulus mounted on and having a central 110 opening larger than said shaft, a reciprocable cone concentric and revolvable with said shafts, means for reciprocating said inner shaft, and a coiled expansion spring pressing said cone toward said annulus. 115

7. An autographic register comprising an upper transverse discharge roller, a tubular shaft, an annulus mounted on and having a central opening larger than said shaft, a solid shaft within said hollow shaft, a reciprocable cone concentric and revolvable with said shafts and secured to said solid shaft by means of a transverse pin extended through a longitudinal slot in the tubular shaft, means for reciprocating said solid 120 shaft, a coiled expansion spring pressing said cone toward said annulus, a transverse rock-shaft adjacent said tubular shaft having an arm that bears endwise against the 125 solid shaft when the cone is out of engage- 130

ment with the annulus, and is made to engage the same laterally when said cone engages said annulus.

8. An autographic register comprising an upper transverse discharge roller, a tubular roller, separate circumferential flanges mounted on said shaft in alignment with postholes formed in the paper strips, an annulus of substantially the same diameter as 5 said flanges having a central opening of greater diameter than the portion of the shaft upon which it is mounted, a reciprocable cone that engages the central opening of said annulus, a solid shaft seated in the 10 bore of said tubular shaft, a transverse pin that extends through a longitudinal slot in said tubular shaft and connects the cone to the solid shaft, a coil expansion spring that pushes the cone into engagement with the 15 annulus, a transverse rockshaft adjacent said tubular shaft, and an arm projecting from one end thereof that bears endwise against the solid shaft when the cone is out of engagement with the annulus and engages 20 it transversely when said cone engages the annulus.

9. The combination in an autographic register with feed rollers, one of which is tubular, a shaft reciprocable within the 25 tubular roller, and a paper strip starter actuated by said shaft, of means for moving said shaft longitudinally.

10. The combination in an autographic register with feed rollers, one of which is 30 tubular, a shaft reciprocable within the tubular roller and having one end extending beyond the said roller, and a paper strip starter actuated by said shaft, of means engaging the outer end of the shaft and adapted 35 to move it longitudinally.

11. The combination in an autographic register with feed rollers, one of which is tubular, a shaft reciprocable within the 40 tubular roller and having one end extending beyond the end of said roller, an annular starter collar loose on said tubular roller, and a cone for centering said collar that is secured to and reciprocated by said shaft, of means 45 designed to reciprocate said shaft.

50 12. In an autographic register, the combination with feed rollers, a reciprocable shaft within the bore of one of said rollers, having a screw-threaded end extending beyond its bearings, an annular starter mounted upon and normally eccentric to said shaft, a cone-shaped head secured to said reciprocable shaft and operable to engage and center said starter, of a device that engages the 55 screw-threaded end of said shaft and returns it to its original position, and means for actuating said device.

60 13. In an autographic register, the combination with the feed rollers, a reciprocable shaft within the bore of one of said rollers, having a screw-threaded end extending 65 be-

yond its bearings, an annular starter mounted upon and normally eccentric to said shaft, a cone-shaped head secured to said reciprocable shaft and operable to engage and center said starter, of an oscillatory device that 70 engages the screw-threaded end of said shaft and returns it to its original position, and means for actuating said device.

75 14. In an autographic register, the combination with the feed rollers, a reciprocable shaft within the bore of one of said rollers, having a screw-threaded end extending beyond its bearings, an annular starter mounted upon and normally eccentric to said shaft, a cone-shaped head secured to said reciprocable shaft and operable to engage and center said starter, of a movable arm having a 80 segmentally threaded recess that engages the screw-threaded end of said shaft and returns it to its original position, and means 85 for actuating said arm.

90 15. In an autographic register, the combination with the feed rollers, a reciprocable shaft within the bore of one of said rollers having a screw-threaded end extending beyond its bearings, an annular starter mounted upon and normally eccentric to said shaft, a cone-shaped head secured to said reciprocable shaft and operable to engage and center said starter, of a manually raised 95 movable arm having a segmentally threaded recess that engages the screw-threaded end of said shaft and returns it to its original position, and means for actuating said arm.

100 16. In an autographic register, the combination with a shaft having thereon feed rollers, a reciprocable shaft carried by the first mentioned shaft and provided with a threaded portion, a movable member which engages the threaded portion of the reciprocating shaft to effect longitudinal movement thereof, and means for effecting a return of 105 said shaft.

110 17. In an autographic register, the combination of feed rollers, a shaft mounted for reciprocation with respect to one of said feed rollers, said shaft having an end portion which extends beyond the end of said feed roller, a strip engaging and feeding means mounted to be normally loose with respect to one of said feed rollers, and a cone-shaped head associated with said shaft and adapted to position said strip-engaging and feeding means concentric with the axis of its supporting roller.

115 18. The combination in an autographic register with feed rollers one of which is tubular, a shaft reciprocable within the tubular roller and having one end extending beyond the end of said roller, an annular starter collar loose on said tubular roller, and a cone for centering said collar that is secured to and reciprocated by said shaft, of a lever designed to permit the reciprocation of said shaft.

19. The combination in an autographic register with feed rollers one of which is tubular, a shaft reciprocable within the tubular roller and having one end extending beyond the end of said roller, an annular starter collar loose on said tubular collar, and a cone centering said collar that is secured to and reciprocated by said shaft, of a rocking lever designed to permit the reciprocation of said shaft and an eccentric device for rocking said lever.

20. In an autographic register, the combination with a shaft having thereon feed rollers, a reciprocal shaft carried by the first mentioned shaft and provided with a screw-threaded extended end, a movable member which engages the screw threaded end of the reciprocating shaft to effect longitudinal

movement thereof, and means for effecting a return of said shaft.

21. In an autographic register, the combination of feed rollers, a shaft mounted for reciprocation within one of the feed rollers, said shaft having an end portion which extends beyond the end of the feed roller in which it is partially housed, a strip engaging and feeding means loosely mounted to be engaged by and positioned to be concentric with the axis of its supporting roller by a cone shaped head associated with the reciprocating shaft.

In witness whereof we have hereunto set our hands this 30th day of January, 1922.

LOUIS JENSEN.
WALTER R. BARKER.
